EDGE ILLUMINATED INSTRUMENT PANEL

Arthur MacArthur, Jr., Fort Worth, Tex., assignor
to Consolidated Vultee Aircraft Corporation,
San Diego, Calif., a corporation of Delaware

Application October 13, 1950, Serial No. 189,963

2 Claims. (Cl. 240—8.16)

1

This invention relates to electric lighting devices and more particularly to illumination of panels by edge lighting thereof.

An object of the present invention is to provide an electric light assembly for edge lighting a panel having an improved construction affording a compact arrangement of parts which presents a minimum of structure protruding from the exterior and visible face of the panel.

Another object of the invention is the provision in a lighting device of the character indicated of a construction whereby it may be readily and easily mounted on a panel and once mounted is securely maintained.

Another object of the invention is to provide an improved construction for a panel illuminating electric lighting device having its component parts particularly formed and organized to facilitate rapid assembly and disassembly thereof whereby the device may be readily removed for replacement or repair.

A further object is to provide a novel form of lighting device having an improved construction which lends itself to economy of manufacture and results in a simplified and efficient structure.

Other objects and features of the present invention will be readily apparent to those skilled in the art from the following specification and appended drawings wherein is illustrated a preferred form of the invention, and in which:

Figure 1 is a longitudinal sectional view of an electric lighting assembly embodying the present invention.

Figure 2 is a perspective view of the retaining element.

Figure 3 is a fragmentary perspective view of a modified form of retaining element.

Figure 4 is a longitudinal sectional view of a modification of the electric light assembly; and

Figure 5 is a perspective view of the retaining element of the light assembly of Figure 4.

In the drawing the numeral 10 indicates a panel and the numeral 11 generally indicates the electric light assembly of the present invention. The panel 10 may constitute an instrument panel, switch panel, circuit breaker panel, radio panel, instruction panel or like member, and may have lettering, indicia, or any variety or form of markings applied thereon which will be illuminated by the rays of light provided in the panel by the electric light assembly 11. The panel is formed of a suitable translucent organo-plastic material which readily conducts light with a minimum loss of light. The material used may be vinyl resin,

2

cellulose acetate or methyl methacrylate which is sold commercially under the trade-mark "Lucite." The rear surface of the panel is preferably smooth and glass-like and will reflect the light inwardly to increase the illumination available at the face of the panel. The desired smoothness of surface is readily attained in the molding operation.

A metallic mounting plate 12 is provided at the rear face of the panel 10 to which the panel 10 is secured in any suitable manner. Suitable means retain the mounting plate 12 in place. It is understood that the precise manner of holding the panel 10 on plate 12 and of securing plate 12 at a desired position forms no part of this invention. An aperture 13 is provided in panel 10 in alignment with an aperture 14 afforded in mounting plate 12, through which apertures the electric light assembly 11 extends for mounting thereof upon panel 10. Surrounding aperture 14 the mounting plate 12 is grooved or recessed at 15 to effect an inwardly directed flange or ledge 16 which assists in the support of the light assembly 11, as will be later described.

Electric light assembly 11 includes a housing 17, a terminal assembly 18 supported at one end of the housing 17, an incandescent lamp 19 enclosed by housing 17 and a metallic retaining member or cap 20. The housing 17 comprises a generally cylindrical shell 21 having an outwardly projecting flange 22 at one end, an internally threaded portion 23 adjacent this one end, and at its other end having its interior surface cut away as at 24 to form an internal shoulder or seat against which a contact carrier ring, or base, 25 made of a suitable insulating material, abuts to close this end of the shell 21. Contact carrier ring 25 forms a part of the terminal assembly 18 and is secured to the end of shell 21 by spinning or staking the end of shell 21, as shown at 26, to project a portion of the shell into an annular peripheral groove 27 centrally provided in the exterior surface of the ring 25. Contact carrier ring 25 is provided with a central aperture 28 in which is mounted a metallic guide bushing or eyelet 29, the interior end of which is outwardly turned as at 31 and pressed into engagement with the interior face of ring 25. Terminal assembly 18 also includes a terminal lug 32, which may be connected in any suitable manner to a source of electrical energy, not shown, and which is supported at the exterior face 33 of ring 25, with a washer 34 interposed between a leg 35 of lug 32 and the face 33 of ring 25. The exterior end of eyelet 29 is turned

to form a flange 36 which clamps the lug 32 and the washer 34 to the ring 25.

A metallic sleeve or conductor element 37 is slidably fitted in the bore of eyelet 29 and extends from within the housing 17 through the eyelet 29, and aligned openings provided in washer 34 and leg 35 of lug 32 to project to the exterior of the housing 17. A contact 38 is carried at the interior end of metallic sleeve 37 for movement therewith. Completing the terminal assembly 18 is a spiral spring 41 which is fitted about and surrounds the interiorly disposed portion of metallic sleeve 37. One end of spring 41 seats upon the turned end 31 of eyelet 29 and the opposite end abuts the rear face of contact 38. Spiral spring 41 exerts its bias to force metallic sleeve 37 forwardly into housing 17. The outer end of metallic sleeve 37 is flared as at 42 for abutting engagement with the eyelet flange 36 to limit the extent of inward movement of sleeve 37 into housing 17.

Movable contact 38 is adapted to be engaged by base contact 43 of incandescent lamp 19 when the latter is inserted into elongated shell 21 through the opening thereof. Lamp 19 is of conventional construction and comprises a glass bulb 44 within which is located a usual filament 45 having one terminal, not shown, connected to base contact 43 and its other terminal, not shown, connected to a metallic sheath 46. To maintain the lamp 19 in operative position within housing 17 there is provided the metallic retaining member or cap 20. Cap 20 may be formed of aluminum or any other suitable conducting metal and as best shown in Figure 2 comprises an annular head portion 47 of greater diameter than aperture 13, and a generally cylindrical body portion 48 having a bore 49 therein. The body portion 48, in the area thereof adjacent head portion 47, is cut away on opposite sides to provide openings 51 and 52 communicating with bore 49 to enable light from lamp 19 to shine through cap 20. Body portion 48 is externally threaded as shown at 53 to engage the internally threaded portion 23 of shell 21 thereby to secure the cap 20 to the shell 21.

Encircling the section of body portion 48 having the openings 51 and 52 is an annular translucent filter member 54 of any desired color which is adapted to lie in aperture 13 of panel 10 with its base resting on flange 22 of housing 17, and being retained in aperture 13 by a rubber washer or cushioned member 55. Washer 55 is of greater diameter than aperture 13 and is disposed on body portion 48 of cap 20 between the filter 54 and the rear surface of the cap's head portion 47 and will be forced against filter 54 and the face of panel 10 when cap 20 is threaded into housing 17. Filter 54 is made of suitable translucent plastic material such as that employed in the manufacture of panel 10 and may be of any desired color to provide colored light within the panel 10 when lamp 19 is on. It has been found advantageous in aircraft usage to light various instruments on the instrument panel with a soft light to lessen the chance of confusion when the viewer transfers his gaze from outside the airplane to the instrument panel. The color red is particularly preferred for an aircraft panel for it provides non-glaring illumination of the instruments. Color also more readily attracts the attention of a viewer and therefore would be useful in connection with a warning device which lights up on the occurrence of a particular condition.

The lower end 56 of body portion 48 is adapted to engage a flange 57 on sheath 48 of lamp 19 to thereby move the lamp 19 rearwardly into housing 17 against the bias of spring 41 as cap 20 is threaded into housing 17. In this movement lamp contact 43 engages movable contact 38 to complete the lamp circuit. To facilitate the movement of cap 20 into housing 17 the head portion 47 is slotted to receive the end of a screwdriver.

To secure housing 17 to mounting plate 12 the housing 17 is externally threaded as at 58 and carries a nut 61, a lock washer 62 and a washer 63.

Figure 1 illustrates the electric light assembly 11 in mounted position on panel 10. Assembly 11 may be attached to panel 10 while in fully assembled position, with lamp 19 in contacts engaged position, the filter 54 disposed adjacent the openings 51 and 52 and cap 20 threaded into shell 21. To mount assembly 11 it is necessary only to insert the housing 17 into the aligned apertures 13 and 14, provided in panel 10 and mounting plate 12 respectively, and move the assembly 11 inwardly until flange 22 on shell 21 abuts ledge 16 on mounting plate 12. Washer 63, lock washer 62 and nut 61 are then fitted on the exterior of shell 21 and nut 61 rotated until washer 63 is tightly pressed against the rear face of mounting plate 12 to clamp ledge 16 between the washer 63 and flange 22 of shell 21. With this construction it is apparent that the light assembly 11 may be easily and readily removed from the panel for inspection, repairs or replacement.

It is to be noted that head portion 47 of cap 20 protrudes only a slight amount beyond the front face of panel 10. The height of head portion 47 is only as great as is necessary to conveniently permit the use of a tool to manipulate cap 20. Holding the height of head portion 47 to a minimum height is of advantage in that it permits easier scanning of the panel lettering and objects, it is much less likely to cause confusion between it and knobs of circuit breakers having deceptively similar appearance, and further it offers less of a hazard to aircraft crew members who work in a small enclosure and who would be much less likely to inadvertently strike against it.

Figure 3 illustrates a modification of a retaining cap member for the electric light assembly. As shown the modified cap member, which is here indicated generally by the numeral 65, comprises an externally threaded body portion 66 having opposed openings 67 and 68, and a head portion 69. Head portion 69 differs from head portion 47 of cap 20 in that instead of employing a slot there is formed a central projection 71 on the front face of the head portion 69, which projection 71 may be grasped by pliers for ready manipulation of the cap member 65. Again the height of head portion 69 is held to a minimum. Head portion 69 with its projection 71 is of not much greater height than head portion 47 with its slot for receiving the end of a screw driver. Only a sufficient height is provided the projection 71 to enable it to be readily grasped by pliers.

The modification illustrated in Figures 4 and 5 differs from the structure hereinbefore described essentially in the form of the retaining cap member and the manner of providing colored light into a panel.

The modification of Figure 4, similarly to the modification of Figure 1, embodies a generally

cylindrical shell 21 having a projecting flange 22 at one end, an internally threaded section 23 adjacent this end, and an internal shoulder 24 at the opposite end. A terminal assembly 18 is supported at this opposite end. This terminal assembly 18, as in the first embodiment, includes an insulating contact carrier ring 25 which is secured to shell 21 by spinning the end of shell 21, an eyelet 29 to which is secured a terminal lug 32, and which guides a metallic sleeve 37 which carries a contact 38. A spiral spring 41 projects the sleeve 37 into shell 21. On insertion of incandescent lamp 19 into shell 21 contact 38 engages base contact 43 of lamp 19.

To retain the lamp 19 in operative position within shell 21 there is provided a cap member 73 which is distinct from cap members 20 and 65 hereinbefore described.

Cap member 73 embodies a metallic generally cylindrical element 74 having an externally threaded portion 75 and a portion 76 of reduced diameter having its exterior surface knurled. An internal groove 77 is provided in portion 75 adjacent the outer end thereof and receives a ring-type spring 78 which exerts its force to support the lamp 19 within cap 73. Secured to the portion 76 of metallic element 74 is a translucent cylindrical element 81 formed of a suitable translucent plastic material which material may be the same as the material used in making panel 10 and filter 54. By employing a translucent element 81 in the construction of the cap member 73 it is obvious that a filter 54 need not be used. The material of the plastic element 81 may be colored, and be of any desired color, for the same purpose as filter 54 is colored.

Translucent cylindrical element 81 is rabbeted at one end and internally as shown at 82 to accommodate the reduced diameter portion 76 of metallic element 74. Plastic element 81 is secured to metallic element 74 by hot-forming the rabbeted portion 82 of element 81 about the knurled exterior surface of portion 76, or may be secured by the use of a suitable commercial nection between elements 74 and 81 forms no cement. The exact method of effecting the connection between elements 74 and 81 forms no part of the present invention and therefore any well known expedient may be employed. Thus the metallic cylindrical element 74 and the translucent element 81 cooperate to form the body portion of cap member 73 which envelops the lamp 19, and to which the lamp 19 is releasably secured by spring 78.

A rabbet 83 is provided at the opposite end of the translucent element 81 and receives a rubber washer or cushion 84. Fitted to this same end of element 81 is a head element 85 formed of hard rubber and comprising a disk portion 86 and a shank portion 87 which projects into the end of element 81. The head element 85 is secured to element 81 either by molding or by the use of a suitable cement. Again the method of connecting one element to the other is not a part of the invention and any conventional method may be utilized. The exterior face of head element 85 is slotted to enable manipulation of the cap member 73 by means of a screw driver. Rather than a slot the face of head element 85 could be formed similarly to head portion 69 of the modified cap member 65 illustrated in Figure 3.

In mounting the modified electric light assembly of Figure 4 the shell 21 carrying the terminal assembly 18 is inserted through aper-

ture 14 of mounting plate 12 to rest flange 22 upon ledge 16. To clamp shell 21 to mounting plate 12 shell 21 carries the nut 61 with interposed washer 63 and lock washer 62. Tightening of nut 61 will effectively secure the shell 21 to mounting plate 12. After the shell 21 has been mounted the panel 10 is placed upon mounting plate 12 and the cap member 73 carrying lamp 19 is inserted through an aperture 88 and rotated to effect a threaded engagement between internally threaded section 23 of shell 21 and externally threaded portion 75 of element 74. It is noted that aperture 88 in panel 10 in the present modification is of smaller diameter than aperture 13 in panel 10 of the first described modification. Aperture 88 does not permit the passage of shell 21 therethrough and is of sufficient size only to accommodate cap member 73. Head element 85 is of greater diameter than aperture 88 and thus when cap member 73 is moved into threaded engagement with shell 21 the cap member 73 exerts a clamping force upon panel 10 and serves to support panel 10 on mounting plate 12. If desired other suitable mounting means, not shown, may be employed to assist in securing the panel 10 to mounting plate 12. In the mounted position of cap member 73 the lamp 19 is positioned adjacent the edges of panel 10 and the light therefrom passes freely through translucent element 81 and into the panel 10 for illumination thereof.

Cap member 73 can be readily withdrawn and will carry lamp 19 with it to permit inspection or replacement thereof.

While certain preferred embodiments of the invention have been specifically disclosed, it is understood that the invention is not limited thereto as many variations will be readily apparent to those skilled in the art and the invention is to be given its broadest possible interpretation within the terms of the following claims.

What I claim is:

1. The combination with a translucent panel of a device for illuminating the panel, said panel having an aperture therein, a mounting plate contiguous the rear face of said panel, a substantially cylindrical elongated shell having an opening aligned with said aperture, threads provided on the interior wall of said shell, means for removably securing said shell to the mounting plate, a contact movably mounted within said shell, a lamp disposed within said shell for projecting light into the edges of the aperture in the panel, a contact on said lamp engaging said movable contact, a retaining means for holding said lamp within said shell with the contacts in engaged position, said retaining means comprising a head portion positioned at the front face of the panel which overlies and closes the aperture in the panel for sealing off said lamp and clamping the panel to the mounting plate and a generally cylindrical body portion having an axial bore therein into which said lamp extends, which body portion projects through the aperture and into the shell, said body portion comprising an externally threaded metallic portion engaging the interior threads of the shell to secure the retaining means to the shell and a translucent portion connecting said metallic portion and said head portion and which lies adjacent the edges of the aperture in the panel to permit the light from the lamp to pass therewith, and spring means carried by

the metallic portion for mounting said lamp to said body portion.

2. The combination with a translucent panel of a device for illuminating the panel, said panel having an aperture therein, a mounting plate contiguous the rear face of said panel, a substantially cylindrical shell opening at one end onto said aperture, threads provided on the interior wall of said shell, means for removably securing said shell to the mounting plate, a terminal assembly carried at the opposite end of the shell comprising an insulating base which closes said end of the shell, a contact, and spring-biased means movably mounting said contact, a lamp disposed within said shell for projecting light onto the edges of the aperture in the panel, a contact on said lamp engaging said movable contact, and retaining means for holding said lamp within said shell with the contacts in engaged position, said retaining means comprising a head portion positioned at the front face of the panel which overlies and closes the aperture in the panel for sealing off said lamp and clamping the panel to the mounting plate and a generally cylindrical body portion having an axial bore therein into which said lamp extends,

5
10

which body portion projects through the aperture and into the shell, said body portion comprising an externally threaded metallic portion engaging the interior threads of the shell to secure the retaining means to the shell and a translucent portion connecting said metallic portion and said head portion and which lies adjacent the edges of the aperture in the panel to permit the light from the lamp to pass into said edges, and spring means carried by the metallic portion for mounting said lamp to said body portion.
